UNITED STATES PATENT OFFICE.

VIRGIL E. KERR, OF FALLS CHURCH, VIRGINIA.

BEDSTEAD ATTACHMENT.

SPECIFICATION forming part of Letters Patent No. 650,466, dated May 29, 1900.

Application filed December 30, 1899. Serial No. 742,101. (No model.)

To all whom it may concern:

Be it known that I, VIRGIL E. KERR, a citizen of the United States, residing at Falls Church, in the county of Fairfax and State of Virginia, have invented a new and useful Bedstead Attachment, of which the following is a specification.

This invention relates to bedsteads in general, and while the principles involved may be applied to a bed of any style the invention relates specifically to and is particularly adapted for use in connection with iron-frame beds.

One object of the present invention is to provide a construction of bedstead in which the entire slat-supporting frame will be yieldably supported and will thus sink in its entirety under the weight of the occupant of the bed instead of yielding only at points, as is the case with the ordinary spring-beds.

A further object of the invention is to provide means for adjusting the height of the slats and correspondingly increasing the length of the path of movement of the slats and their support to compensate for increased weight upon the bed, an additional object of the invention being to permit inclining of the slats in order that the ends thereof next to the head may be raised and lowered with respect to the opposite ends, and vice versa.

In the drawings forming a portion of this specification, and in which similar numerals of reference designate like and corresponding parts in the several views, Figure 1 is a perspective view showing a complete bedstead constructed in accordance with the present invention. Fig. 2 is a vertical section of the lower portion of one of the posts of the bedstead, taken transversely of the bedstead and showing parts of the interior mechanism in elevation and illustrating also the connection of one of the slat-supports and the location of the slats thereon. Fig. 3 is a transverse section of one of the end supports for

the slats and showing the end of an adjacent slat engaged therewith. Fig. 4 is a transverse section of one of the foot-posts of the bedstead and taken on a line just above the rails. Fig. 5 is an elevation showing the middle slat-support with its adjustable mem-

bers, the operative positions of these adjustable members being indicated in dotted lines. Fig. 6 is a plan view showing the mutually-adjacent ends of the supplemental slat-supports and a part of the support to which they are attached, the ends of the supplemental supports being shown as connected by pins passed through alining perforations therein.

Referring now to the drawings, the bedstead of the present invention comprises head-posts 5 and 6 and foot-posts 7 and 8, each of which consists of a tube of suitable length. The head-posts 5 and 6 are connected by means of cross-braces 9 and 10, which have attached thereto the usual spindles 11, the foot-posts having also connecting-braces 12 and 13, to which are secured spindles 14, the posts being thus rigidly connected to form a head and a foot.

At a suitable distance from the lower end of each post is formed a flange 15, the outer faces of which are flattened and lie at right angles to each other. Secured to one flat outer face of each of the blocks 15 of the posts 7 and 8 is a foot-rail 16, while to the adjacent outer faces of these flanges are secured side rails 17 and 18, having their opposite ends secured to the corresponding faces of the flanges upon the head-posts 5 and 6. Secured also to the flanges of the head-posts is a head-rail 19, these rails and posts being rigidly secured together to form the frame proper of the bedstead.

In the adjacent sides of the foot-posts 7 and 8 are formed slots 20, which extend longitudinally thereof and terminate at their upper ends substantially in the plane of the upper surfaces of the rails of the bedstead. These slots extend downwardly to points adjacent the lower ends of the posts, and they lead into the interior of the posts. Similar slots 21 are formed in the inner faces of the head-posts 5 and 6.

The lower end of each of the posts 5, 6, 7, and 8 is interiorly threaded, as shown at 22 in Fig. 2 of the drawings, and with these threads is engaged the stem 23 of a plate 24, upon which is pivotally mounted a caster 25. This stem 23 acts as a plug for the lower end of the post and also forms a seat upon which

rests the lower end of an interiorly-threaded tube 26, which is disposed within the post, and while fitting snugly therein may be readily applied and removed.

5 The tube 26 forms one member of a screw-jack, of which the other member is formed by a screw 27, which may be adjusted with respect thereto to cause its upper end to lie at different points of the inclosure of the posts.

10 Adjacent the upper end of the screw 27 is a flange 28, beyond which an unthreaded portion 29 of the screw extends, and this flange 28 receives directly the lower end of a helical spring 30, which encircles the unthreaded portion 29, this spring extending upwardly within the posts and being movable with the element 27 of the jack.

15 Slat-supports 31 are disposed with their ends projected inwardly through the slots 20 and 21, respectively, these slat-supports being disposed one adjacent the head-rail 19 and another adjacent the foot-rail 16 and parallel therewith. Upon the lower faces of the end portions of the slat-supports are formed 25 lugs 32, which enter the inclosures of the upper ends of the springs 30, which latter rest upon the under faces of the slat-supports, and thus the slat-supports are in turn supported yieldably by the springs 30.

20 The slat-supports are provided with recesses 33, in which the slats are disposed flush with the upper faces of the supports, and by means of which recesses they are held properly spaced, said slats being prevented 35 from longitudinal displacement by depending portions 34 at their ends, which lie upon the outer faces of the slat-supports. As illustrated in Figs. 1 and 2, flexible connections, such as chains 35, are attached to the slats in 40 order that they may be kept together when disengaged from their supports.

Additional posts 36 and 37 are connected with the side rails 17 and 18 intermediate their ends, and these posts 36 and 37 are in 45 all respects the same in construction and arrangement as the head and foot posts, with the exception that they do not extend above the side rails. A third slat-support 38 is disposed with its ends in slots in the inner faces 50 of the posts 36, and the ends of this support lie upon helical springs within the posts in the same manner as above described.

In the present structure both the slats and the slat-supports are formed rigid, and thus, 55 if a weight be placed upon the bed, when the mattress is in place the bed will not sink in spots corresponding to the contour of the body, but will sink bodily, and will thus maintain the even surface of the bed, excepting 60 for the yielding of the mattress itself.

When it is desired to adjust the springs 30 for any reason, the casters may be removed and the tubes 26 may then be drawn out of the posts and the screw 27 adjusted to the 65 proper extent. The jack may then be returned to the posts and the parts adjusted to

the position shown in Fig. 2 of the drawings. It will furthermore be seen that the present structure permits the inclination of the slats to be adjusted to any angle by correspondingly adjusting the jacks, and that when a thick mattress is employed its upper surface can be caused to lie at the same height as would the upper surface of a thinner mattress. 70

When the slat-supports 31 are raised above 75 the side rails of the bedstead, it is of course necessary to provide a support for the slats intermediate its ends above the support 38, the upward movement of which is limited by the height of the posts 36 and 37. For this 80 purpose supplemental supports 40 are provided. There are two of these supplementary supports, each of which is somewhat more than half as long as the support 38. One of the supplementary supports is connected to 85 one side of the support 38 and adjacent one end thereof by means of links 41, while the other supplementary support is connected by means of links 41 with the opposite side of the support 38 and adjacent the opposite end 90 thereof. Thus the supplementary supports may be swung upwardly to lie above the main support, their lengths being such that when in this position their adjacent ends will overlap. These overlapping ends are transversely 95 perforated, as shown at 46, and the perforations of one supplementary support are adapted to align with the perforations of the other. When the perforations are aligned, a pin 45 is passed through any two of the alining perforations to hold the two supplementary supports connected and to prevent them falling to their lowered positions. By shifting the pin the altitudes of the supplementary supports may be changed, as will be readily understood, and by inclining the links of both 100 supplementary supports inwardly said supports are prevented from rotary displacement by pressure of the bed-slats thereon. The supplemental supports are thus held in their 105 elevated positions and the end supports 31 may be correspondingly adjusted.

It should be noted that the vertical adjustment of the slat or mattress supports (it being understood that in the event that a spring 115 bed-bottom or mattress is employed it may be arranged directly upon the transverse bars or supports located, respectively, at the head and foot of the bedstead-frame and at an intermediate point thereof) is accomplished by 120 the bodily adjustment of the means whereby these supports are upheld, such means in the construction illustrated consisting of springs and the movable members of the jacks, both springs and jacks being housed in the seats 125 or cavities formed by the bores of the hollow uprights of the bedstead-frame, and being held against downward displacement by the casters, of which the stems are fitted removable in the lower ends of said ores. 130

It will of course be understood that in practice the specific structure shown may be va-

ried and that the invention itself may be applied to any bedstead to which it is adapted and that any desired materials and proportions may be used without departing from 5 the spirit of the invention.

What is claimed is—

1. A bedstead having posts, vertically-movable slat or mattress supports, and bodily adjustable and yieldable means carried by the 10 post for upholding the supports and varying their normal elevations, and means for adjusting the upholding means.

2. A bedstead having posts, vertically-movable slat or mattress supports, means including bodily-adjustable springs, carried by the 15 posts for upholding the supports to vary their normal elevations, and means for adjusting the upholding means.

3. A bedstead having posts, vertically-movable slat or mattress supports, and means for upholding the supports, the same consisting 20 of springs, and screw-jacks having their adjustable members arranged to support the springs at different elevations, and correspondingly vary the normal positions of the 25 supports.

4. A bedstead having posts, vertically-movable slat or mattress supports, and means for upholding the supports, the same consisting 30 of springs, and means for effecting the bodily vertical movement thereof to vary the normal elevations of the supports.

5. A bedstead having posts provided with 35 cavities, slat or mattress supports, springs and adjusting devices housed within said cavities and bodily removable therefrom, the slat or mattress supports being upheld by the springs, and means for securing the adjusting devices in fixed positions with relation to the 40 posts.

6. A bedstead having posts provided with 45 cavities, slat or mattress supports, springs and adjusting devices housed within said cavities and bodily removable therefrom, the slat or mattress supports being upheld by the springs, and means for securing said springs and adjusting devices in place in the cavities, said means consisting of removable casters.

7. A bedstead having hollow posts, slat or 50 mattress supports, springs and jacks housed within said posts, and bodily removable therefrom, the slat or mattress supports being upheld by the springs, and casters removably fitted in the lower ends of the posts for upholding the jacks.

8. A bedstead having hollow posts open at 55 their lower ends, slat or mattress supports, springs and screw-jacks housed within the posts for upholding said slat or mattress supports, said springs being supported by the adjustable members of the jacks, and casters removably fitted in the lower ends of the cavities of the posts and forming seats for the lower ends of the jacks.

9. A bedstead having posts, bodily-adjustable upholding means carried by the posts,

transverse supporting-bars upheld by said means and independently adjustable to vary their normal relative elevations, longitudinal slats seated upon the supporting-bars and 70 means for adjusting the transverse bars independently.

10. A bedstead having posts, bodily-adjustable upholding means carried by the posts, transverse supporting-bars upheld by said 75 means, and independently adjustable to vary their normal relative elevations, said supporting-bars having longitudinally-aligned seats, longitudinal slats supported by and fitting the seats of said bars, flexible connections between the slats and means for adjusting the transverse bars independently.

11. The combination with a bedstead comprising hollow slotted posts, of a sleeve disposed slidably within each post and having 85 interior threads, a screw engaged with the threads of the sleeve, a spring mounted upon each screw, slat-supports passed through the slots and resting upon the springs, and removable means for holding the sleeves from 90 sliding movement in the posts.

12. The combination with a bedstead comprising hollow slotted posts having interior threads at their lower ends, of an internally-threaded sleeve disposed slidably in each post, 95 a screw engaged with each sleeve, a spring resting upon each screw, slat-supports passed through the slots and lying upon the springs, and casters having threaded stems engaging the interior threads of the posts, to hold the 100 sleeves from displacement.

13. In a bedstead, the combination with hollow slotted corner-posts having rails connected therewith below the upper ends of the slots, of a spring in each post, slat-supports 105 engaging the springs, means for adjusting the springs to raise and lower the supports, additional hollow slotted posts connected with the rails, springs in the last-named posts, a slat-support having its ends engaged with 110 said springs, means for adjusting the springs to raise and lower the last-named support, and supplemental slat-supports having link connections with the last-named support for projection to lie above the rails when the first-named slat-supports are correspondingly placed.

14. In a bedstead, the combination with hollow slotted corner-posts having rails connected therewith below the upper ends of the 115 slots, of a spring in each post, slat-supports engaging the springs, means for adjusting the springs to raise and lower the supports, additional hollow slotted posts connected with the rails, springs in the last-named posts, a 120 slat-support having its ends engaged with said springs, means for adjusting the springs to raise and lower the last-named support, supplemental slat-supports having link connections with the last-named support for projection to lie above the rails when the first-named slat-supports are correspondingly 130 placed.

placed, and to lie with their adjacent ends overlapped, perforations in the adjacent ends of the supplemental supports and adapted to aline when said supplemental supports are projected above the rails, and a pin for engagement with alining perforations to hold the supplemental supports projected.

In testimony that I claim the foregoing as my own I have hereto affixed my signature in the presence of two witnesses.
